(57) **CLAIM**

The ornamental design for a nozzle, as shown and described.

DESCRIPTION

FIG. 1 is a perspective view of a nozzle in accordance with the present design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a first end elevation view thereof; and,

FIG. 7 is a second end elevation view thereof, opposite the first end.

The broken lines showing the remainder of the nozzle are for environmental purposes only and form no part of the claimed design.
